SOUND GENERATING AUDIOMETER

Clayton D. Mullin, St. Paul, and Harold W. Darr, Minneapolis, Minn., assignors to Maico Electronics, Inc., Minneapolis, Minn., a corporation of Minnesota

Filed May 9, 1960, Ser. No. 60,490

Term of patent 14 years

(Cl. D83—12)

FIG. 1

FIG. 2

FIG. 3

FIG. 4

FIG. 5

FIG. 6

FIG. 1 is a front elevational view of a sound generating audiometer embodying our new design;

FIG. 2 is a right side elevational view thereof, the left side not shown being substantially the same as the right side shown;

FIG. 3 is a rear elevational view thereof;

FIG. 4 is a top plan view thereof;

FIG. 5 is a bottom plan view thereof; and

FIG. 6 is a detail sectional view thereof taken approximately at 6—6 in FIG. 3.

We claim:

The ornamental design for a sound generating audiometer, substantially as shown and described.
